No. 664,553.

Patented Dec. 25, 1900.

E. F. HUGHES.

EXHAUST VALVE FOR STEAM ENGINES.

(Application filed Jan. 15, 1900.)

(No Model.)

UNITED STATES PATENT OFFICE.

EDWARD F. HUGHES, OF BOSTON, MASSACHUSETTS.

EXHAUST-VALVE FOR STEAM-ENGINES.

SPECIFICATION forming part of Letters Patent No. 664,553, dated December 25, 1900.

Application filed January 15, 1900. Serial No. 1,511. (No model.)

To all whom it may concern:

Be it known that I, EDWARD F. HUGHES, a citizen of the United States, residing in Boston, in the county of Suffolk and State of Massachusetts, have invented certain new and useful Improvements in Exhaust-Valves for Steam-Engines, of which the following, taken in connection with the accompanying drawings, is a specification.

- 10 My invention relates to the exhaust-valves used in the pipe-line connecting steam-engines with the condenser. As prime movers of this description are usually installed a pipe leads from the exhaust of the engine to a T-fitting and a pipe from this latter to the condenser, including between the T-fitting and the condenser a stop-valve, so the connection to the condenser may be closed when required. The other branch of the T-fitting 15 connects with a check-valve opening to the atmosphere whenever the pressure on the side of the check-valve next the T-fitting exceeds the air-pressure. The check-valve acts as a safety device to permit the engine to exhaust into the atmosphere if the vacuum in the condenser fails from overheating or derangement of the air-pump, while the stop-valve serves to cut off the condenser from the engines, so it may be repaired.
- 20 The arrangement above described is expensive and occupies considerable space. To overcome these objections, I have devised a special fitting; and the invention consists in providing the said fitting with connections to the exhaust of the engines, a stop-valve to shut off the condenser, and an automatic relief-valve to give access to the atmosphere.
- 25

A good embodiment of the invention might have a chamber with flanged inlets, so that engines may be connected to either or both sides. A valve opening into this chamber connects it with a passage that terminates in a flanged opening that may be connected to the condenser. A threaded stem from this 30 valve rises through a stuffing-box and, in connection with a nut supported by a yoke attached to the fitting, enables the engineer to manipulate the valve by the hand-wheel fastened to the nut. Another passage having a flanged extremity for connections to the atmosphere leads from the chamber and is provided with a valve opening into the pas-

sage at its junction with the chamber. This relief-valve is adapted to open if the pressure in the chamber exceeds the pressure in the 55 passage, but may be operated by a hand-lever connected with a stem passing through a stuffing-box and attached to the valve when necessary, and to prevent too sudden movement of the valve the hand-lever is connected 60 with a dash-pot. In some cases it is convenient to have several valves connecting the chamber with the leading passages instead of a single valve.

If the steam plant is working under normal 65 conditions, the valve controlling the passage to the condenser is open and the valve leading to the atmosphere is closed. If anything happens so the condenser is unable to dispose of the exhaust-steam of the engines, the 70 pressure will rise in the chamber of the fitting, and when it exceeds the pressure of the atmosphere the valve of the passage leading from the chamber thereto will open to give vent to the exhaust of the engines. If the 75 interruption should be serious and render it necessary to get at the condenser, the valve leading from the chamber of the fitting to the condenser is closed, so that repairs may be made. When the condenser is ready for use 80 again, the valve connecting it with the chamber of the fitting is opened with the hand-wheel, and for a brief period the chamber of the fitting is in connection with the exhaust of the engines, the atmosphere, and the condenser. The relief-valve is now brought 85 gradually to its seat, the vacuum meanwhile constantly improving, and the final seating of the valve is cushioned by the dash-pot to prevent slamming. The means taken to insure 90 slow closing of the relief-valve are of considerable importance if the engines are furnished with an oversensitive governor, as the additional effective pressure due to the condenser tends to racing.

The fitting is illustrated in detail in the accompanying drawings, in which—

Figure 1 is a vertical central section of the fitting. Fig. 2 is an elevation of the right-hand portion of Fig. 1. Fig. 3 is a partial 100 elevation of the left-hand side of Fig. 1. Fig. 4 is a plan of Fig. 2. Fig. 5 is a horizontal section of the chamber, inlets, and outlets on line X X of Fig. 1. Fig. 6 is a horizontal sec-

tion through the passage leading to air on line Y Y of Fig. 1.

The body of the fitting *a* is furnished with flanges *b* and *c* at the extremities of the inlets *d* and *e*, connecting with a chamber *f*, so that engines may be connected to both inlets; but one of the inlets, as *b*, may be covered by a disk *g* if the engines feed only into the other inlet. Conveniently arranged with relation to the inlets are the flanges *h*, *i*, and *w* of the passages *j* and *k*, connecting with the chamber *f*. One, as *j*, leads from the flange *h* up and over the chamber *f*, and at its junction therewith a valve *l* is arranged to open into the passage *j*. The other passage *k* dips under the chamber, and a valve *m*, opening into the chamber, controls their junction. A hollow stem *n* is connected to the valve *l*, so the valve may revolve on the stem and be lifted or forced to its seat by the hand-lever *o*, pivoted to the stem and having a link connection with a yoke *p*, attached to the cover of the passage *j*. A suitable stuffing-box formed in the said cover prevents the escape of steam around the stem *n*. The cover also supports a dash-pot *q*, connected by a link with the hand-lever *o* to retard the motion of the valve. A rod *r* passes through the stem *n*, and the valve *m* is attached to its extremity, so the valve may revolve thereon, but be positioned with relation to its seat by the hand-wheel *s*, fastened to the nut *t*, which is arranged to revolve in the yoke *p*, but is restrained from axial motion therein. A stuffing-box connected to the end of the stem *n* prevents the escape of steam around the rod *r*.

The exhaust of the engines might be connected to the flange *c* of the fitting. The valve *m* under ordinary working conditions would be open and the valve *l* would be closed, so the exhaust-steam would pass to the inlet *e*, then the chamber *f*, through the valve *m*, to the passage *k*, and to the condenser through a pipe connected to one of the flanges *i* or *w*, as may be suited by the position of the condenser, so the lead will be the more direct from the fitting, the flange not connected being of course covered by a disk. If now the condenser fails, the increase of back pressure in the chamber *f* opens the valve *l* and permits the steam to enter passage *j*, so it may escape into the atmosphere by means of a pipe connection to the flange *h*. If it becomes necessary to shut off the condenser, the valve *m* is seated by the hand-wheel *s*, fastened to the nut *t*, threaded on the rod *r*, which is attached to the valve. If the engines have been exhausting into the air and it is desired to connect them to the condenser, the valve *m* is opened and the relief-valve *l* is brought slowly to its seat by the hand-lever *o* through its connection with the stem *n*, which latter is attached to the valve *l*. The final seating of the valve is retarded by the dash-pot *q*, which is connected by a link with the hand-lever *o*.

If the engines are to exhaust into the air, it is advantageous to keep the relief-valve from fluttering, and for this purpose I push the pin *u*, which slides in a hole in the yoke *p*, through a hole *v* in the hand-lever *o* and into a registering hole in the yoke on the opposite side of the slot in the yoke for the hand-lever.

Having described my invention, I claim and desire to secure by Letters Patent of the United States—

1. In an exhaust-valve, the combination with an integral body having a fluid inlet or inlets connecting with two distinct discharge-passages, of a valve normally positioned by the fluid-pressure on its opposite sides to control one passage, and a valve positioned independently of the impressing fluids to govern the other passage, substantially as described.

2. In an exhaust-valve, an inlet-chamber having connections with several passages, combined with valves operated only by hand for some of the passages, and valves adapted to be opened by abnormal pressure of the fluid in the chamber, for other passages, substantially as described.

3. In an exhaust-valve, a passage provided with a valve and connected devices to govern it by hand, combined with a passage furnished with a valve normally closed by air-pressure, having means for retarding its motion, that is arranged to be opened by unusual pressure of a fluid in an inlet-chamber contiguous to both valves, substantially as described.

4. In an exhaust-valve, a chamber having suitable inlets; a valve, with a threaded stem and adapted to be positioned by a nut which is restrained in a yoke attached to the fitting, for governing a passage from the chamber; and a valve, having a pivoted hand-lever attached to its stem and connections with a dash-pot, arranged to open from the chamber into a separate passage, automatically upon excessive pressure in the chamber but also subject to control by the connections with the hand-lever, substantially as described.

5. In an exhaust-valve, a single structure having a stop-valve to govern one passage leading from the inlet-chamber, combined with an independent relief-valve to control another passage leading from the chamber, the latter valve being connected with a hand-lever having attached thereto a retarding device and having means for locking the said valve away from its seat, substantially as described.

6. In an exhaust-valve, the combination in a single structure having means for admitting a fluid, of valves for its outlets, the controlling-rod of one valve being arranged within the stem of the other, and one of the valves having connections with a retarding device, substantially as described.

7. In an exhaust-valve, a valve and connected devices for moving it by hand to govern a passage, combined with a valve having

means for retarding its motion and normally actuated by the atmosphere to close a second passage, but that is arranged to be opened by unusual pressure of a fluid in an inlet-chamber contiguous to both valves, substantially as described.

8. In an exhaust-valve, a body having a chamber, provided with suitable inlets; a valve, with its stem threaded in a nut which is axially restrained in a yoke attached to the fitting, but free to be revolved by any suitable means, so the valve may govern a passage from the chamber; and a valve, having a controlling hand-lever attached to its stem

and connections with a retarding device, arranged to open from the chamber into a separate passage, automatically upon excessive pressure in the chamber but also subject to control by the attached hand-lever, substantially as described.

In testimony whereof I have hereunto subscribed my name this 2d day of January, A. D. 1900.

EDWARD F. HUGHES.
